WARPING APPARATUS

Burt A. Peterson and Brooks Marcellus, Rockford, Ill., assignors to Barber-Colman Company, Rockford, Ill., a corporation of Illinois

Application October 14, 1935, Serial No. 44,932

6 Claims. (Cl. 28-39)

This invention relates to warping apparatus, i. e., to apparatus for simultaneously rewinding the yarn of a considerable number of supply yarn masses onto a single relatively large container. Such an apparatus comprises a creel for supporting the supply yarn masses and a warper for supporting and rotating the receiving container or "warp beam". The invention has special applicability to warping apparatus that is intended to run at high speed, e. g., approximately one thousand yards per minute, as the desirability of rapidly accelerating the warp beam upon starting the apparatus and the necessity of promptly stopping the rotation of the warp beam upon the breakage or undue slackening of a yarn have created problems that were difficult of solution. In this connection it may be pointed out that with a broken thread-end traveling at the rate of about one thousand yards per minute it is essential to stop the warp beam promptly, lest the thread-end become wound upon the beam and covered with windings of yarn so that it cannot be found and tied to the broken end on the supply yarn mass. The application of the necessary braking force to the heavy winding drum and the warp beam to cause prompt stoppage, without producing destructive stresses, is one of the problems to which the present invention is directed.

The invention is in the nature of an improvement upon the warping apparatus disclosed in the Peterson Patents Nos. 1,780,318 and 1,872,179, particular reference being made to Fig. 6 of the first-mentioned patent and Figs. 1 and 2 of the second. As shown in those patents, the warper 30 was driven from a belt pulley through a mechanically operated clutch and was stopped by means of a mechanically operated brake. The mechanism required for the proper acceleration and deceleration of the warp beam was relatively complicated and subject to excessive wear and breakage.

The general object of the present invention is to obtain rapid, controlled acceleration and deceleration with reduced liability to wear and breakage; and this object has been attained, in part, by the substitution, as far as possible, of electrical apparatus for the mechanism of the prior art.

In the accompanying drawings

Figure 1 is a plan view of a warping apparatus embodying the features of this invention, the rear part of the creel being broken away.

Fig. 2 is a horizontal sectional view taken along the axis of the friction drum that supports and rotates the warp beam.

Fig. 3 is a fragmental sectional view of the brake and clutch.

Figs. 4, 5 and 6 are views of one of the "drop wires" or "detectors" located on the creel, and the control bar therefor.

Fig. 7 is a diagram showing the mechanism and electric circuits through which the warping apparatus is controlled, showing the condition of the apparatus after it has been stopped through the dropping of a drop wire or through the action of the warper clock. The drop wires are in the drag position illustrated in Fig. 4, and the rest cam shaft is in the first or stopped position of rest, as in Fig. 8.

Figs. 8, 9 and 10 are views illustrating different positions of the cams that control various switches.

Fig. 11 is a fragmental view of the rock shaft and connections that control the drop wires.

In Fig. 1, A denotes the warper, B the creel, and C a warp beam mounted in the warper.

Warper

The framework of the warper A comprises a base 1 and two side frames 2 and 3. Rotatably mounted in bearings attached to the side frames is a shaft 4 (Fig. 2). To this shaft is fixed a drum 5 that supports and frictionally drives the warp beam C. The means for driving the drum 5 includes a pulley 6 rotatably supported on the right-hand end of the shaft 4, ball bearings 7 being interposed between the shaft and the hub of the pulley. Belts 8 communicate power to the pulley 6 from a pulley 9 (Fig. 1) on the shaft of an electric motor 10. The pulley 6 revolves continuously while the motor 10 is running. Power is transmitted from the pulley 6 to the drum shaft 4 through a magnetically-actuated friction clutch 11 which may be of any preferred construction, as, for example, of the type disclosed in Warner Patent No. 1,981,208, dated Nov. 20, 1934. Herein the clutch is shown as comprising a clutch drum 12 rigidly secured to the outer end of the shaft 4 and having an internal clutch or friction surface 13 arranged for engagement by an expandable clutch-band 14 (Fig. 3). An annular electromagnet 15 is supported on the pulley 6, for a slight amount of rotation relative to the pulley. A slip ring of conventional design conducts current to the magnet. The latter is adapted to attract an armature ring 16 rigidly connected to the clutch drum 12. A spring 17 connected to end brackets 18 of the clutch-band 14 tends to contract the clutch-band. Between the end brackets 18 is an abutment 19 on the pulley 6. Lugs 20 on the magnet 15 are arranged to

50 connect to the clutch drum 12. A spring 17 connected to end brackets 18 of the clutch-band 14 tends to contract the clutch-band. Between the end brackets 18 is an abutment 19 on the pulley 6. Lugs 20 on the magnet 15 are arranged to

abut against surfaces of the end brackets 18 of the clutch-band, the spring 17 holding said surfaces against said lugs when the magnet is not energized. When the magnet is energized, it 5 attracts the armature ring 16 which is fixed to the drum 12 and hence to the shaft 4. The magnet and the clutch-band are thus caused to lag as the pulley 6 revolves, whereby the abutment 19 and one of the lugs 20 act to spread apart the 10 ends of the band and thereby cause the pulley 6 and the drum 12 to be frictionally clutched together. It will be noted that the clutch just described applies power to the drum shaft 4 as directly as possible.

15 The means for promptly arresting rotation of the drum 5 comprises a magnetically operated friction brake 21 which is similar to the clutch 11, and hence need not be described in detail. 22 is a brake drum rigidly secured to the left-hand end of the drum 5, and 23 is a brake band connected to the side frame 3 and arranged to be expanded into frictional engagement with the internal surface of the drum 22 by means including an electromagnet 24 mounted on the side 25 frame. It will be seen that the braking torque is applied directly to the drum 5 and is not transmitted through a shaft or keys.

Creel

30 The creel B may be of any desired form. Herein I have shown a creel generally similar to the one disclosed in the before-mentioned Peterson patents and comprising two upright frames 28 which are adjacent to each other at one end 35 and separated at the opposite end so as to constitute a V-shaped structure. The supply yarn masses or "cheeses" a are non-rotatably supported in the creel frame for the drawing of the yarn off the ends of the cheeses. The drop wires 40 for guiding the yarn in its course from the cheeses to the warper and for closing an electric circuit upon the breakage or excessive slackening of a yarn are arranged in vertical rows in front of the cheeses that are being unwound. Their 45 location is indicated at b in Fig. 1 and their construction is shown in Figs. 4, 5 and 6.

Each drop wire consists of a piece of wire bent to form a yarn-guiding arm 26 and a horizontal pivot 27 which is grounded as indicated in Fig. 7. 50 Upon the pivot 27 is mounted a contact arm 28 which is arranged to swing into contact with an electric conductor 29 for the purpose of closing a circuit to stop the warper when the drop wire is permitted by a broken or slack yarn to swing 55 into the position shown in Fig. 4.

Means is provided to effect three results, namely, to cause all of the remaining drop wires to assume the position shown in Fig. 4 in order to place a drag on the yarns upon the stoppage of the warper; to hold all of the drop wires up in the position shown in Fig. 5 when the yarns from a new set of cheeses are to be drawn forward to the warper; and to free the drop wires, as shown in Fig. 6, so that they shall be held up only by the yarns after the warper has been restarted. Said means comprises a control bar 30 for each vertical row of drop wires, each bar having for each drop wire a projection 31 adapted to engage the contact arm 28 and an arm 32 fixed to the pivot 27. The control bars 30 are connected for simultaneous movement through the medium of bell cranks 33 (Fig. 7) and a connecting bar 34. As shown in Figs. 4, 5 and 6, the control bars 30 are arranged to occupy three 75 positions,—the normal or running position il-

lustrated in Fig. 6, the stopped position represented in Fig. 4, and the rethreading position shown in Fig. 5. The means for causing the control bars to assume these positions comprises a bell crank 35 connected to the bar 34 and a rod 36 connecting the bell crank 35 to an arm 37. Said arm is fixed on a shaft 38 and is rigid with an arm 39 (Fig. 11). The latter is arranged to be operated automatically to produce the control bar positions shown in Figs. 4 and 6, and manually to produce the control bar position illustrated in Fig. 5. The manual control is effected through a hand lever 40 pivoted in the warper frame in position for access by the operator while standing in front of the warper (see Fig. 1). 15 A connecting rod 41 extends from the lever 40 to the arm 39, a pin 42 on said arm lying within an elongated opening 43 in the connecting rod. A spring 44 tends to hold the pin 42 against the forward end wall of the opening. 20

An arm 45 is loosely mounted on the shaft 38 and has a releasable connection with the arm 39. Said releasable connection in the form herein shown consists of a latch 46 pivoted on the arm 39 and adapted to engage in a notch 47 in the 25 arm 45. A spring 48 normally holds the latch in the notch. Rigid with the latch 46 is an arm 49 arranged to be engaged by a cam 50 on the rod 41. The parts are so proportioned that when the hand lever 40 is pulled forward, the cam 50 30 will engage the arm 49 and throw out the latch 46 before the rear end wall of the opening 43 engages the pin 42, after which continuing forward movement of the hand lever 40 will cause movement of the arms 39 and 37, the rod 36, the 35 bell crank 35, the bar 34 and the control bars 30 to place all of the drop wires in the position shown in Fig. 5.

The arm 45 is rigid with an arm 51 carrying an antifriction roller that bears on a cam 54. 40 The arm 39 is rigid with an arm 52 that carries an antifriction roller bearing on a cam 53. The cams 53 and 54 are fixed on a resetting cam shaft 55 which is arranged to be driven by an electric motor 56 (Fig. 7) through the train 57, 45 58, 59, 60, 61, 62 and 63.

Thread roll and its brake

The several hundred yarns extend from the drop wires to a thread roll 64 (Figs. 1 and 7) and 50 thence to the warp beam. The high speed at which the warping is done necessitates the application of a brake to the thread roll when the warp is being stopped, since if the thread roll were permitted to coast to a stop it would either 55 damage the yarn at the point of contact with the roll or else draw yarn from the cheeses, thus producing slackness in the yarn between the thread roll and the warp beam, which slack yarn would kink and cause trouble in subsequent 60 operations. A brake 65 is therefore provided, said brake being applied by a spring 66 and withdrawn by a cam 67 on the reset cam shaft 55. The connection between the brake and the cam includes an arm 68 rigid with the brake, an arm 65 69 bearing on the cam, and a link 70 extending between said arms.

General description of electric circuits and resetting mechanism

70 Before describing more particularly the electric circuits and the means whereby the circuits are opened and closed in the operation of the warper and the creel, it may be stated that, in the present embodiment of the invention, the electromag- 75

nets 15 and 24 for the clutch 11 and the brake 21, respectively, are operated on a low voltage direct current, which is obtained from a 110-volt alternating current line through the use of a transformer 71 and a dry-plate rectifier 72 (Fig. 7). It may also be stated that the reset cam shaft 55 makes one revolution per cycle of operation, but in three steps, the shaft thus having three rest positions. To move from one rest position to the next it is, of course, necessary to start the motor 56. These three rest positions of the cam shaft 55 are illustrated in Figs. 8, 9 and 10.

Fig. 8 shows the first or "stopped position", which is the position taken by the cam shaft 55 when the warper is stopped. In going to this position the double cam 53-54 lifts the control bars 30 to their highest position, as shown in Fig. 4, wherein the drop wires are caused to place a drag on that portion of the yarn which extends between the drop wires and the warper. The drop wire circuit and the circuit of the motor that drives the cam shaft also are opened.

In going from the stopped position to the second or "accelerating position" the warper is started. The cam shaft 55 halts in the accelerating position until the warper has been accelerated to a speed great enough to place sufficient tension on the yarn to hold up the drop wires. When this speed has been attained, a centrifugally-actuated switch 73 (Fig. 7) closes a circuit that again starts the cam shaft 55 in rotation. The switch 73 may be of any preferred type, and is responsive to the speed of the drum 5, the switch contacts being open when the warper is stopped and being closed when a certain speed is attained.

While turning from the accelerating position to the third or running position, the shaft 55 lowers the control bars 30 to the position shown in Fig. 6, wherein the drag is removed from the yarn and the drop wires freed so that they are held elevated by the running yarn, whereupon a controlling switch in the drop wire circuit is closed so that the falling of a drop wire shall complete that circuit; and the circuit of the speed-responsive switch is opened.

Restarting after stoppage through action of drop wire

50 The diagram, Fig. 7, represents the condition of the apparatus when the warper is at rest after having been automatically stopped by reason of the breakage or excessive slackness of a yarn. The circuit through the clutch magnet 15 is open, but the circuit through the brake magnet 24 is complete, as follows: transformer 71, rectifier 72, wire 78, normally closed switch 19, wire 80, normally closed contacts 13^a of a relay 13^b, wire 13^c, rheostat 73^d, magnet 24 and wire 73^e to ground.

60 The operator finds the broken end on the beam and draws forward to the warper the broken end attached to the cheese. After piecing up the broken yarn, the operator presses a lever 74 on the warper, thereby closing a switch 75, and completing a circuit to ground through wire 76, the coil of a reset relay 11, and wire 84 to line.

65 The energization of the reset relay coil 77 causes the lower set of contacts 81 to close thereby completing a circuit through the reset motor 56 as follows: contacts 81, wires 82 and 83, motor 56, and wire 84 to line. The lever 74 must be held depressed long enough to permit the cam shaft 55 to revolve sufficiently to close a switch 85 through the action of a cam 86 on said shaft, after which the lever 74 may be released. The

opening of the switch 15 deenergizes the relay 11, but the closing of the switch 85 maintains a circuit through the reset motor 56 as follows: wires 87 and 88, switch 85, wires 82 and 83, motor 56 and wire 84 to line. When the cam 86 reaches the position shown in Fig. 9, the switch 85 opens, whereupon the motor stops with the reset cam shaft 55 in the second or accelerating position. The rotation of the cam shaft has caused the thread roll brake 65 to be released.

10 In going from the first or stopped position (Fig. 8) to the second or accelerating position (Fig. 9), a cam 89 on the shaft 55 closes a switch 90, thereby establishing a circuit as follows: wires 87 and 91, switch 90, wire 92, normally closed contacts 93 of the reset relay 11, wires 94 and 95, coil of brake and clutch relay 13^b and wire 97 to line.

15 The energization of the coil of the relay 13^b opens the switch 13^a of the brake circuit and closes a switch 98, thereby establishing a circuit 20 through the clutch magnet 15 as follows: transformer 71, rectifier 72, wire 78, switch 19, wire 80, switch 98, wire 99, rheostat 100, wire 101, magnet 15 to ground, thus causing the warp beam to be 25 revolved.

20 When moving from the first to the second position of rest, a cam 102 on the shaft 55 closes a switch 103, thereby closing at that point a circuit through the reset motor 56 which is completed as soon as the warp beam has been sufficiently accelerated to hold up the drop wires, 30 as follows: wire 84, motor 56, wires 83, 82 and 105, switch 103, wire 106, switch 73, and wire 107 to ground, thereby restarting the motor 56.

25 In the turning of the shaft 55 from the second or accelerating position to the third or running position, the switch 90 remains closed, thus keeping the clutch circuit closed and the brake circuit open; the cam 53-54 lowers the control bars 30, thus removing the drag on the yarn and freeing 40 the drop wires so that they may thereafter be held up by the yarn; and a switch 108 is closed by a cam 109 on the shaft 55. The closing of the switch 108 supplies current to the conductors 29, through a wire 110, so that if any drop wire 45 shall fall, a circuit shall be closed to stop the warper, and also supplies current to a circuit through wire 111 that includes a warper clock 112 so that the warper shall be stopped upon the completion of the beam.

30 As the shaft 55 reaches the third or running position, the switch 103 is opened, thereby opening the circuit of the motor 56, whereupon the shaft 55 comes to rest in the running position shown in Fig. 10.

35 It will be seen that the setting of the warp beam in rotation is dependent upon closing of the switch 90, and that this occurs while the cam shaft 55 is turning from the first to the second position of rest. Stoppage of the beam, however, 60 is not dependent upon rotation of the shaft 55, the beam brake being applied as the direct result of the closing of a circuit, as will presently appear, stoppage thus being effected promptly.

65 *Stopping through action of a drop wire or the clock*

70 In the event of breakage or undue slackness of a yarn, the corresponding drop wire completes a circuit to ground as follows: pivot 27, contact 70 arm 28, conductor 29, wire 110, switch 109, wire 84, coil of relay 11, and wire 84 to line. The resulting opening of the relay contacts 93 breaks the circuit of the relay 13^b, which in turn opens the clutch circuit and closes the brake circuit, 75

thus promptly stopping the beam. The energization of the relay 71 also closes a holding circuit through the relay as follows: wires 87 and 81, switch 90, wires 92 and 113, contacts 114, wires 115 and 76, coil of relay 77 and wire 84 to line. The energization of the relay 77 also closes the contacts 81, whereby a circuit is closed through the motor 56 as follows: wires 82 and 83, motor 56, and wire 84 to line. The shaft 55 thereupon moves from the third or running position to the first or stopped position, which causes the cam 53-54 to lift the control bars 30 so as to place the drop wires in drag position (Fig. 4); opens the drop wire circuit through the opening of switch 108; and opens the circuit of motor 56 through the opening of switch 90. After correcting the trouble that caused closing of the drop wire circuit, the operator restarts the apparatus as before described.

Completion of the beam causes stoppage as in the event of drop wire operation.

Stopping at will from high speed

When the apparatus is running at high speed, with the reset cam shaft 55 in the third or running position, stoppage may be effected at will by depressing the lever 74. This completes a circuit through the coil of reset relay 77, as described in connection with starting, which, in turn, opens the circuit of the relay 73b at the contacts 93 (thereby causing release of the clutch and application of the brake), and completes a circuit through the motor 56, thereby causing the cam shaft 55 to be turned from the third or running position to the first or stopped position, and effecting stoppage of the apparatus as described in connection with the subject of stopping through the action of a drop wire or the clock.

Low-speed rotation of beam

When restarting, whether after piecing up a single yarn or when starting a new beam or at any other time, it is usually desirable to be able to rotate the beam slowly so as to observe whether all of the strands are running properly before inaugurating a cycle of operation that will bring the warper to full speed. For this purpose there is provided a normally open switch 116 arranged to be closed by depression of a pedal 117. Closure of the switch 116 completes a circuit through the coil of the brake and clutch relay 73b, as described in connection with the subject of restarting after stoppage through action of a drop wire, thereby releasing the brake and applying the clutch. The pedal is kept depressed long enough to enable the operator to see that all the strands are running properly, after which the pedal is released, and the lever 74 depressed to start a cycle of operations of the reset cam shaft 55 from the first to the second and then to the third rest position.

Brake for reset motor 56

It is necessary that the shaft 55 shall come to rest in its predetermined positions. In order to prevent overrunning of the motor 56, shaft 55 and connecting drive, a brake is provided. In the present instance the brake is shown as consisting of a brake drum 118 on the motor shaft, and a brake band 119 which is normally pressed against the drum by a spring 120. Whenever the motor circuit is closed a shunt circuit 121, 122 is closed through a magnet coil 123, the armature of which coil is connected to a bell crank lever 124 to slacken the brake band. As soon as the motor circuit is broken, the spring

120 applies the brake band and prevents overrun through momentum.

Beam guard

In order to protect the operator against injury, there is provided a beam guard comprising end portions 125 and a transverse portion 126, the end portions being pivoted in the warper framework so that the guard may be swung from a position wherein the portion 126 extends in front of the beam to an elevated, out-of-the-way position. The beam guard must be raised before a warp beam can be placed in or removed from the warper.

In order that it shall not be possible to start the warper unless the beam guard is in its lower or effective position, means is provided whereby the beam guard controls a switch 128a. This switch is associated with the clock 112, and is arranged to be closed through contact of the beam guard with a cam 126b attached to the movable switch point. When the switch 128a is closed, a circuit is closed to ground, as when a drop wire falls or the clock operates. The warper cannot then be restarted and placed in full speed.

Beam arm safety switch

The warp beam C may be supported upon the driving drum 5 by any desired means, as, for example, by means of pivoted beam arms as disclosed in the Colman Patent No. 1,366,447. With the construction shown in the Colman patent, in order to remove the beam from the warper when it is full, it is necessary to raise the beam arms slightly. This additional movement of one of the beam arms is availed of to open the switch 79 in the circuit controlled by the relay 73b so that if the pedal 117 were accidentally depressed no current would be supplied to the clutch magnet 15 to cause rotation of the drum 5. At the same time, the circuit of the brake magnet 24 is broken, so that the beam may be rotated by hand, which is desirable when the new set of yarns is brought to and wrapped around the beam.

As indicated diagrammatically in Fig. 7, the movable contact of the switch 79 tends to move away from the other, and is normally kept in closed position by a spring-actuated detent 127 that normally engages a stem 128 connected to the movable contact. A lever 129 is connected at one end to the detent 127 and is arranged at its other end to be moved to withdraw the detent. A cam 130 mounted on the left-hand beam arm bears on the lever 129. When said arm is raised to permit removal of the full beam, the cam 130 trips the detent 127 and allows the switch 79 to open. The cam 130 is so adjusted on the beam arm that when the beam is full any further upward movement of the beam arm will cause tripping of the detent. When starting up a new beam the operator closes the switch 79 by pushing the stem 128 inwardly.

Stopping warper at any time before the high speed or running position (Fig. 10) is reached

To stop the warper it is necessary to de-energize the relay 73b. This, in turn, requires energization of the relay 71 to open the contacts 83, which may be done by depressing the lever 74, as when starting. If, therefore, the warper is running, but the cam shaft 55 has not yet reached the third or running position, depression of the lever 74 will cause throwing out of the clutch and application of the brake. The en-

ergization of the relay 71 also closes the holding circuit 87, 91, 90, 92, 113, 114, 115, so that the relay 71 remains energized during the interval between the closing of the switches 80 (Fig. 9) and 108 (Fig. 10); consequently the motor circuit 81, 82, 83, 56 and 84 is maintained closed, and the cam shaft 55 runs through the second and third rest positions without stopping until it reaches the first or stopped position. All of the cam-actuated switches 108, 103, 85 and 90 are then open (see Fig. 8), the opening of the switch 90 causing interruption of the holding circuit, with consequent deenergization of the relay 71 and hence opening of the motor circuit at the contacts 81.

Starting a new beam

Before drawing forward the new yarns to the warper, the operator pulls the lever 40, thereby freeing the control bars 30 from the control of the cam 53-54 and lowering said bars to their lowest position, as shown in Fig. 5, whereby all of the drop wires are brought into the position illustrated in that view and held there. After the yarns have been connected to the beam, the beam guard is lowered, the safety switch 79 is closed, and the lever 40 operated to raise the control bars 30 to the position shown in Fig. 4 and return them to the control of the cam 53-54. The beam may then be slowly rotated by use of the pedal 111 until all the threads are seen to be running properly, after which the warper may be started as before described.

It will be evident from the foregoing description of the present embodiment of the invention that means has been provided whereby the apparatus may be put through a definite starting cycle in which the warp beam is rapidly accelerated, the drop wires being rendered ineffective until the beam has been sufficiently accelerated, and whereby sufficient braking power may be applied to produce very prompt stoppage of the beam without setting up destructive stresses.

While the construction shown in the drawings has been described in considerable detail, it should be understood that the invention is not limited to the arrangements shown, except as indicated in the appended claims.

In certain of the claims the expression "a stopping circuit" has been used to denote the drop wire circuit 110, the warper clock circuit 111 or an equivalent circuit. In certain claims the term "manual" has been employed to refer to the hand lever 14 or the pedal 117, or an equivalent means operated by the operator.

We claim as our invention:

1. A warping apparatus having, in combination, a creel for the supply yarn masses, a circuit containing a set of drop wires for the yarns from said supply masses, means to place the drop wires in position to place a drag on the yarns and to remove them from such position, means for rotating a warp beam to which said yarns extend, a reset motor for actuating said drop wire means to remove the drop wires from drag position, means to start the reset motor, means actuated by the reset motor for starting the beam-rotating means, means actuated by the reset motor for stopping said motor, a circuit containing means responsive to acceleration of the beam for restarting the reset motor to actuate said drop wire means to remove the drop wires from drag position, to close the drop wire circuit, and to open the second mentioned circuit.

2. A warping apparatus having, in combina-

tion, a creel for the supply yarn masses, a circuit including a set of drop wires for the yarns from said supply masses, said drop wires being arranged to ground said circuit, means for rotating a warp beam to which said yarns extend, said beam-rotating means being arranged to be stopped through grounding of said circuit, a reset motor arranged to be started through the grounding of the drop wire circuit, means driven by the reset motor for placing the drop wires in position to place a drag on the yarns, and means driven by the reset motor for stopping said motor.

3. A warping apparatus having, in combination, means for rotating a warp beam, a clutch and a brake for said beam-rotating means, a circuit for the clutch, a circuit for the brake, a warper relay for opening one and closing the other of said circuits, a circuit for the warper relay, a switch in the warper relay circuit, a reset motor, a circuit for the motor, a switch in the motor circuit, a circuit-closer responsive to the speed of the beam, said circuit-closer being in a branch of the motor circuit, a switch in said branch, a reset relay for alternately closing the motor circuit and opening the warper relay circuit, a stopping circuit connected to the reset relay, a switch in the stopping circuit, and means driven by the motor for operating said switches in the following order: close motor circuit switch, close the warper relay switch, close the switch in the circuit-closer branch circuit, open the motor circuit switch, close the stopping circuit switch and open the switch in the circuit-closer branch circuit.

4. A warping apparatus having, in combination, means for rotating a warp beam, a clutch and a brake for said beam-rotating means, a circuit for the clutch, a circuit for the brake, a warper relay for opening either one and closing the other of said circuits, a circuit for the warper relay, a switch in the warper relay circuit, a reset motor, a circuit for the motor, a switch in the motor circuit, a circuit-closer responsive to the speed of the beam, said circuit-closer being in a branch of the motor circuit, a switch in said branch, a reset relay for alternately closing the motor circuit and opening the warper relay circuit, a stopping circuit connected to the reset relay, a switch in the stopping circuit, and a shaft driven by the motor for operating said switches through a cycle of operation in a single revolution of the shaft, said shaft having three positions of rest and being arranged to operate the switches in the following order: close motor circuit switch, close the warper relay switch, close the switch in the circuit-closer branch circuit, and open the motor circuit switch while moving from the first to the second rest position, and close the drop wire circuit switch and open the switch in the circuit-closer branch circuit while moving from the second to the third rest position, and open the switch in the stopping circuit and the switch in the warper relay circuit while moving from the third to the first rest position.

5. A warper having, in combination, a friction drum for rotating a warp beam, a shaft for said drum, a clutch on said shaft for driving said drum, a brake acting directly on said drum for stopping the drum, a relay tending to energize the brake and de-energize the clutch, a circuit for said relay, a switch in said circuit, a reset motor, a cam driven by the reset motor for opening and closing said switch, and manually operable means to start the reset motor.

5 6. A warper apparatus having, in combination, a friction drum for rotating a warp beam, clutch means for driving said drum, brake means for stopping said drum, electromagnetic means for effecting engagement of either one and disengagement of the other of said means, a circuit including a circuit-closer responsive to the speed of the beam, a circuit including a reset motor, a switch in the reset motor circuit, a switch for

said electromagnetic means, a switch in the circuit-closer circuit, manually operable means for starting the reset motor, and means driven by the reset motor for closing said switches in the order stated and for then opening the switch in 5 the reset motor circuit.

BURT A. PETERSON,
BROOKS MARCELLUS.

CERTIFICATE OF CORRECTION.

Patent No. 2,172,850.

September 12, 1939.

BURT A. PETERSON, ET AL.

It is hereby certified that error appears in the printed specification of the above numbered patent requiring correction as follows: Page 1, first column, line 31, for the patent number "1,780,318" read 1,790,318; and that the said letters Patent should be read with this correction therein that the same may conform to the record of the case in the Patent Office.

Signed and sealed this 10th day of October, A. D. 1939.

(3-17-1)
Henry Van Arsdale,
Acting Commissioner of Patents.

6. A warper apparatus having, in combination, a friction drum for rotating a warp beam, clutch means for driving said drum, brake means for stopping said drum, electromagnetic means for effecting engagement of either one and disengagement of the other of said means, a circuit including a circuit-closer responsive to the speed of the beam, a circuit including a reset motor, a switch in the reset motor circuit, a switch for

said electromagnetic means, a switch in the circuit-closer circuit, manually operable means for starting the reset motor, and means driven by the reset motor for closing said switches in the order stated and for then opening the switch in 5 the reset motor circuit.
